UNITED STATES PATENT OFFICE.

GILBERT C. McCULLOUGH, OF DETROIT, MICHIGAN, ASSIGNOR TO PREMIER PRODUCTS COMPANY, OF DETROIT, MICHIGAN, A CORPORATION OF MICHIGAN.

UPHOLSTERY FILLING DEVICE.

Application filed April 24, 1925. Serial No. 25,566.

This invention relates to devices for the insertion of filling material into tubular envelopes or devices and more particularly to the insertion of fibrous batts into the tubular pleats of upholstery.

By my invention I propose to make use, in a measure, of a method well-known in various arts of filling tubular envelopes or devices which involve the carrying of the filling material in a core or tube into the envelope or tubular device to be filled and thereafter withdrawing the core from the envelope (or the envelope from the core as the case may be), leaving the filling material in the said envelope.

Sometimes the cores have been formed of a plurality of elements such as parallel paddles or a pair of straight, curved or flanged walls which, whilst they may not strictly be referred to as a tube, nevertheless serve the same purpose.

The idea of inserting a filling into a tubular envelope by means of an enclosure which is inserted thereinto with the filling and withdrawn therefrom leaving the filling in place, I recognize as old and do not wish or intend to indicate as being the essence of this invention in its broad sense; but an important object of this invention is the provision of such a device wherein the core includes a plurality of sections disposed one above the other and forming the core proper, which sections are capable of vertical relative expansion and contraction throughout practically their entire length, whereby a firm and even compression of the filling material may be effected during its insertion into a tubular envelope and such compression relieved throughout practically the entire length of the inserted filling material during the withdrawal of the core from the said envelope.

A further object is to provide for the practically complete enclosure of the material during its insertion into the said tubular envelope, and particularly at the forward end of the filling so that tendency of the same to bind on the material of the envelope and tear or otherwise add difficulty to the filling operation is minimized.

The invention further aims to provide a core for the purposes indicated comprising upper and lower members hinged together at one end so that one of the parts may be swung on its hinge to a substantial extent to

permit of free access to the interior of the core for facilitating the extending or positioning of filling material therein and also by means of such hinge construction to permit the raising of one member from the other to an extent sufficient to relieve compression on the filling material therein contained without necessarily resulting in the actual separation of the two members of the core at any point in their length.

A still further object is to provide a compound hinge in the manner suggested or a hinge having such freedom of movement that movement of the hinged member of the core outwardly of the other member thereof may be effected irrespective of or in addition to the swinging movement permitted by the hinge, so that the diameter of the core may be increased or decreased adjacent the said hinge as well as at the forward end of the core. In other words, with the said members of the core arranged one above the other, the upper member may be vertically movable in approximately parallel relation to the lower member as well as swingable at an angle thereto.

Still further objects subsidiary to or resulting from the aforesaid objects, or from the construction or operation of the invention as it may be carried into effect, will become apparent as the said invention is hereinafter further disclosed.

In carrying the said invention into effect I may provide, as a means of facilitating the filling of tubular envelopes with fibrous material, a core of tubular formation, including upper or lower members having downwardly and upwardly extending lateral marginal portions, the lateral portions of one member overlapping those of the other, the lower member being provided with a flared tubular handle portion through which the fibrous material may be introduced to the core and the upper member hingedly attached to the inner end of the said flared tubular portion. These two members are preferably of approximately the same length as the tubular envelopes to be filled, so that they may be passed completely thereinto, and the forward end of the upper member is notched to permit access to the filler contained in the core so that it may be held against removal during the withdrawal of the core from the envelope. In a preferred form of the device the said hinge is of double

or compound construction so that a vertical movement of the hinged member of the core at the hinged end of the said member is permitted irrespective of the swinging movement thereof.

All of which is more particularly described and ascertained hereinafter by way of example, having reference to the accompanying drawings, wherein—

10 Figure 1 is a perspective view of a core embodying the said invention;

Figure 2 is a transverse section illustrating such a core inserted in a tubular envelope such as the pleat of upholstery, the upper 15 and lower members of the tube being contracted together on the filling material;

Figure 3 is a similar view to Figure 2, illustrating the upper and lower members as being expanded against the walls of the 20 envelope by the said filling material;

Figure 4 is a longitudinal section illustrating the core and filling inserted in a tubular pleat of upholstery and the filling being held preparatory to the withdrawing of the 25 core from the pleat;

Figure 5 is a broken plan view of a preferred modified form of the device;

Figure 6 is a side elevation of the same showing the parts of the core in their closed 30 or relatively contracted position;

Figure 7 is a similar view to Figure 6 showing the parts in their expanded position; and

Figures 8, 9, 10 and 11 indicate various 35 cross sections of core members which may be utilized.

Similar characters of reference indicate similar parts in the several figures of the drawings.

40 The device illustrated in Figures 1 to 4 will first be described, although the features of this device are also to be found in the arrangement Figures 5 to 7 which will be hereinafter further referred to.

45 The core comprises upper and lower members 1 and 2, both of these members being of approximately semi-elliptical configuration in cross section, and the upper member having downwardly flanged lateral portions 50 3 adapted to enter between upwardly flanged lateral portions 4 of the lower member 2.

Attached to or integral with the rear end of the lower member 2 is a flared tubular portion 5 through which fibrous material 55 such as a length of cotton batt may be introduced into the core as is clearly apparent in Figure 4, and the upper member 1 of the core is attached to this tubular member 5 by means of a hinge 6, so that it may swing upwardly thereon. Obviously this said member 1 may be swung upwardly to a sufficient extent to allow full access to the trough-like member 2, so that the positioning of filling material therein may be very easily 60 effected, although if desired the filling of

the core may be effected with the member 1 in its closed position over the member 2 by simply feeding the filling material between the said members through the flared portion 5 of the device wherein the nature of the filling material is such that it lends itself to this method of introduction.

As before stated, the core is intended to be passed completely into a tubular envelope such as the tubular pleat of upholstery, this being indicated by the reference numeral 7 in the drawings, and the upper member 1 may be depressed upon the lower member 2, compressing the batt and permitting its ready introduction into the envelope, as 80 shown in Figure 2, during which period pressure of the hand or otherwise on the upper part of the envelope is sufficient to retain the core in its contracted form.

Upon release of such pressure, however, 85 the expansion of the filling material will result in the expansion of the core, as indicated in Figure 3, to the fullest extent permitted by the tubular pleat, thereby relieving the pressure of the walls of the core on the filling material to a substantial extent; and under these conditions the said core may be easily withdrawn from the pleat whilst the filling material is held against such withdrawal such as by means of the 90 pressure of the thumb on the end thereof as indicated in Figure 4. To admit of the thumb being so applied, a notch 8 is preferably formed in the forward end of the said upper member 1.

The end of the lower member 2 it is preferred to form so that it will extend substantially to the end of the pleat as shown in Figure 4 and forms a guide which assists in the carrying of the filling throughout the 105 full length of the said pleat and tends to prevent said filling passing beneath the underside of the member 2, at the same time it forms a pressure plate upon which the filling is compressed by the thumb as shown in Figure 4, preparatory to the withdrawing 110 of the core from the pleat, this pressure plate being smooth and tending to facilitate the initial sliding movement between the core and the filling material when the withdrawal of the said core is commenced, so that there is not the same tendency of the end of the filling to break away from the remainder of the filling in the tube as might otherwise be experienced.

115 It will be apparent that the expansion of the core by the filling material when pressure on the core has been relieved as explained extends throughout practically the whole length of the core so that binding of the filling material in the core is not likely to be experienced, particularly where the core is properly designed and proportioned to suit the nature and size of the pleat with which 120 it is to be used.

It will be further obvious that such a device may be utilized with filling material supplied in rolls of substantial lengths, so that as the core is withdrawn from a pleat 5 it is simply passed rearwardly over the filling material extending from that part thereof which remains in the pleat, and the lower forward end of the member 2 may be abruptly lifted upon its withdrawal from the pleat, 10 thereby severing the filling material and leaving the core in a reloaded state ready for insertion into another pleat, and so on.

To still further ensure the expansion of the core throughout its length preparatory to 15 withdrawal from a pleat, I prefer to use a compound hinge such as that indicated in Figures 5, 6 and 7, from which figures it will be seen that the upper part 10 of the core is capable of being raised substantially 20 throughout its length with respect to the lower part 11 as will be apparent from a comparative examination of Figures 6 and 7. Consequently great freedom is permitted 25 the filler in the core after pressure thereon has been relieved.

Figure 8 illustrates sectional configurations of the upper and lower members of the core of the type indicated in Figures 1 and 4.

Figure 9 illustrates a core of approximately 30 hexagonal configuration, the upper member 12 having angularly bent lateral portions 13 terminating in flanges 14, and the lower portion 15 having angularly bent lateral portions 16 terminating in flanges 17 which overlap the flanges 14 of the upper member.

In Figure 10 the upper and lower members 18 and 19 are of approximately semi-circular sectional configuration, with their 40 meeting edges overlapped, and in Figure 11 the upper and lower members 20 and 21 are of channeled configuration in cross section with their side walls 22 and 23 respectively 45 overlapping.

In this device it will be apparent that no resiliency in the device itself is depended upon to secure the functioning in the manner described, so that the material of which it is 50 made is simply a matter of choice and con-

venience and it admits of very simple construction, although at the same time being very efficient and reliable in its operation, effectively meeting the requirements as to operation of such a device in handling more or less frail filling material and effecting a compact and complete filling of tubular envelopes. 55

This invention may be developed within the scope of the following claims without departing from the essential features of the said invention, and it is desired that the specification and drawings be read as merely illustrative and not in a limiting sense, except as necessitated by the prior art. 60 65

What I claim is:—

1. Means for introducing fibrous material into tubular envelopes, comprising a core longitudinally divided into two members, a compound hinge connecting one end of one 70 of the members to an end of the other member and permitting an outward parallel movement of one of the members relative to the other member as well as a swinging movement thereof. 75

2. Means for introducing fibrous material into tubular envelopes, comprising a tubular member and an elongated member extending therefrom and adapted to receive filling material, a similar elongated member hinged 80 to the tubular member and overlying the first named tubular member to form an enclosure therewith, whereby said elongated members may be manually compressed on said material and expanded by said material when 85 manual compression is relieved.

3. Means for introducing fibrous material into tubular envelopes, comprising an elongated member having an enclosing portion formed at one end, and another elongated 90 member movably mounted with respect to said portion and adapted to form an enclosure with said first named member, whereby said elongated members may be manually compressed on said material and expanded by said material when manual pressure is relieved. 95

In testimony whereof I affix my signature.

GILBERT C. McCULLOUGH.
